RAILWAY CAR TRUCK WITH BOLSTER DAMPENING MEANS

James A. Shafer, East Cleveland, Ohio, assignor, by mesne assignments, to Midland-Ross Corporation, Cleveland, Ohio, a corporation of Ohio

Filed Apr. 2, 1962, Ser. No. 183,599
18 Claims. (Cl. 105—197)

This is a continuation-in-part application which discloses and claims subject matter common to the James A. Shafer application, Serial No. 83,041 filed January 16, 1961 and now abandoned.

This invention relates to railway car trucks which include a friction system for dampening the vertical oscillation of a bolster relative to a side frame thereof. It further relates to an improved arrangement facilitating the removal of friction wedges and springs associated therewith.

The prior art discloses various arrangements of bolster and side frame structure overlapping in a longitudinal direction of the frames to prevent substantial movement between the bolster and side frames in a transverse direction. Generally, these arrangements are not a part of the aforementioned friction system. However, in railway vehicles of American design in prevailing use, repairing or replacing parts in the friction system and the longitudinally overlapping bolster and frame structure, e.g., cooperating bolster lugs and column surfaces, are among the most common instances of car truck repair and maintenance. Also, attrition and, hence, maintenance are substantial with respect to those surfaces of the bolster, the frame, and the friction wedge engaging as the result of the wedging relation of the wedge with the frame and the bolster.

To accomplish such maintenance, it is necessary to remove the car truck from the vehicle and to disassemble the truck. For example, to replace friction wedges, it is generally necessary to separate a side frame from the bolster extending therethrough. Such separation necessitates a lifting of one frame from the car axles while simultaneously lifting (or lowering, with some types of frames) the bolster and shifting the car frame sideways to obtain horizontal disengagement of the bolster and side frame. Such maintenance not only involves substantial labor costs entailed in removing a vehicle from service, making the actual repairs, and returning the vehicle to service but, also, loss of revenue that would be otherwise derived from "down" time of one to several days.

Hence, a primary object of this invention is to provide a railway car truck enabling replacement of its friction wedges and friction wedge springs without any disassembly involving separation of a bolster and side frame, or detachment of the truck from its parent vehicle.

It is an object also to be able to service and repair the friction snubbing system of the truck of a railway car in any condition of loading thereof in a matter of minutes.

It is a further object to provide a railway car truck in which the wear sustained by the bolster snubbing mechanism is restricted to inexpensive castings which are readily removable through the windows of the side frame and in so doing, to eliminate wear on the frame and the bolster.

It is another object to provide a car truck that utilizes a bolster and side frame free of longitudinally overlapping structure conventionally provided for restricting movement of the bolster transversely relative to a side frame. This eliminates the wear and maintenance which is entailed, e.g., in conventional bolsters with "guide lugs." It is particularly desirable to be able to shift the bolster endwise through both side frames of a truck while the truck stands on a track after being removed from under the car, until an end of the bolster is withdrawn from

one side frame. The bolster may then be withdrawn from the other side frame in a reverse direction.

An object closely related to the foregoing is to be able to withdraw the bolster from a side frame at any level within the bolster opening to thus reduce the time, equipment, and labor needed for assembly and disassembly of car trucks as compared to that expended in the maintenance of car trucks in prevalent use.

Other objects, features, and advantages of the invention will become apparent as the invention is described in detail with respect to a car truck which utilizes a friction wedge for interlocking its bolster and one or both side frames, and a chock which is removable from a position between the wedge and a support of the frame to enable the removal of a spring or other cushion means, and then the wedge, from the frame through an opening between the walls without otherwise disturbing the truck.

Broadly speaking, the invention is embodied in a car truck comprising a side frame having a pair of vertically-

extending columns spaced in a longitudinal direction of the frame to define a bolster-receiving opening; a bolster extending in a direction transversely of the frame through its bolster-opening in vertical guide relation with the columns; a friction wedge disposed against one side of the bolster and in a second opening in the adjacent column extending lengthwise of the frame away from the bolster opening; a chock standing between the wedge and a fixed support in the frame; and a cushion, such as a spring, urging the wedge into wedging relation with the chock and the bolster. The second opening extends past one vertical extremity of the support and is large enough for passage therethrough of the chock, the spring, and the wedge. The chock and the support have cooperating portions overlapping in a direction away from the wedge. These overlapping portions dispose the chock and the support in projecting and re-entrant relationship along a vertical plane of cross section extending longitudinally of the side frame and thus prevent movement of the chock relative to the support as long as the wedge is in its wedging position. The chock is movable out of overlapping relation with the support when the wedge is retracted sufficiently upon corresponding yielding of the cushion from its wedging position. The wedge and the chock are of widths less than the transverse distance between adjacent lateral walls of the side frame to permit their removal from therebetween and outwardly through the second opening to a window of the frame. In a preferred embodiment, the bolster has a vertically rectilinear recess in registry with the second opening for receiving a portion of the wedge.

In the drawing with respect to which the invention is described below in detail:

FIG. 1 is a fragmentary lateral elevation, partly in section, of a railway car truck in accordance with one embodiment of the invention;

FIG. 1a is a longitudinal elevation of a car truck comprising the car truck components shown in FIG. 1;

FIG. 2 is a fragmentary plan view partly in section of the portion of the car truck illustrated in FIG. 1;

FIG. 3 is an elevation in section looking longitudinally of the side frame of FIGS. 1 and 2 taken along line III—III of FIG. 1;

FIG. 4 is a fragmentary section taken along the horizontal plane indicated by line IV—IV of FIG. 1 with the wedge spring omitted to expose the spring seat shown;

FIG. 5 is a fragmentary perspective view of the side frame of FIG. 1 illustrating a method for removing the chock of FIG. 7;

FIGS. 6 and 7 are perspective views of a friction wedge and a wedge-supporting chock, respectively; a corner portion of the wedge is broken away in FIG. 6 to illustrate the wall arrangement thereof;

FIG. 8 is a fragmentary lateral elevation, partly in

section, of a railway car truck in accordance with another embodiment of the invention;

FIG. 9 is a fragmentary perspective view of the side frame of FIG. 8;

FIG. 10 is a fragmentary side elevation illustrating a modified side frame and a modified friction wedge in a position of passage through a window of the frame;

FIG. 11 is a fragmentary side elevation of the side frame of FIG. 10 illustrating a wedge spring in a position of passage through the window, and the friction wedge positioned above its operative position with one corner thereof horizontally opposite the upper end of the chock support;

FIG. 12 is a fragmentary elevation of the side frame of FIGS. 10 and 11 in longitudinal cross section illustrating one critical stage in passing the wedge spring into operative position;

FIG. 13 is a fragmentary elevation of the side frame of FIGS. 10 to 12 in longitudinal cross section showing the wedge spring resting on a rib at a stage of assembly preceding positioning thereof on its normal seat in the frame;

FIG. 14 is a fragmentary elevation of the side frame of FIGS. 10 to 13 showing the friction wedge depressed and the wedge spring correspondingly compressed to permit insertion of a chock;

FIG. 15 is a fragmentary elevation of the side frame of FIGS. 10 to 14 illustrating the wedge, chock, and wedge spring in normal operative position;

FIG. 16 is a perspective view of the friction wedge employed in the use of the side frame of FIGS. 10 to 15;

FIG. 17 is a diagrammatic view of geometric relationships of the chock support, the chock, and the wedge with the bolster;

FIG. 18 is a fragmentary view of a spring seat portion of the side frame as viewed along line XVIII—XVIII of FIG. 12.

With attention now to the first embodiment to be described, as illustrated in FIGS. 1 to 5, FIG. 1 is a fragmentary view of a car truck illustrating, in elevation, a truss-type side frame 4 of conventional overall proportions comprising: an upper compression member 5 and a lower tension member 6 spaced at the middle of the frame by a pair of columns 7 and 8. The columns are spaced in the longitudinal direction of the frame to provide a bolster opening 10. The compression and tension members meet in a junction (not shown) at opposite ends of the truss adjacent to a conventional journal box or pedestal type end portion.

As shown in FIG. 2, a bolster 12 extends through the bolster-receiving opening of the side frame with an absence of parts of either the side frame or the bolster overlapping in a longitudinal direction of the side frame. The bolster shown is supported on a plurality of springs 14 which stand on a spring seat 15 defined by the middle portion of the tension member 6. The bolster is arranged to provide a downwardly facing spring seat 16 engaging the upper ends of the springs 14.

As shown more clearly in FIGS. 2 and 4, the columns 7 and 8 comprise vertically extending portions separated in a transverse horizontal direction of the side frame. For example, column 7 comprises spaced webs 18 and 19 which face across the opening 10 toward column 8. These webs, along with vertical and longitudinally extending webs or side walls 21 and 22, define an opening 23 contiguous with the bolster opening 10 and extending therefrom in a longitudinal direction of the side frame.

As shown most clearly in FIG. 4, the bolster 12 has a vertically rectilinear recess 25 in each of its lateral longitudinally facing walls agreeing closely in horizontal width in the transverse direction of the side frame with the opening 23 as defined between the webs 18 and 19. As shown, the recess 25 is formed by a wear plate 26 secured to the bolster between an upper lip 28 and a lower lip 29. With the aid of these lips, a couple of light

fillets of welding material secure the wear plate to the bolster in a satisfactory manner. FIG. 4 further shows a wedge 30 positioned within the bolster recess 25 and the opening 23 with a vertical rectilinear friction surface 31 thereof engaged face-to-face with the bottom of the recess, i.e., surface 32. The width of the wedge, in the horizontal transverse direction of the side frame, closely agrees, except for a slight clearance, with the spacing between webs 18 and 19 and the out-turned edges of the wear plate 26. With the wedge supported by a spring 35 to cause the wedge to engage a chock 36 and the recessed surface 32, the bolster is substantially interlocked from longitudinal movement relative to the frame. However, as the truck must accommodate transverse movement of the side frames relative to the bolster in its movement over a track of which the rails have lateral irregularities, a desired limited relative movement of the bolster 12 and the side frame 4 in the transverse direction of the side frame is provided by the above-mentioned clearance.

Therefore, to a great extent, the wedges 30 function as guides for the bolster 12 in effecting vertical rectilinear movement relative to the side frame. This is even true in respect to any movement of the bolster in a longitudinal direction of the frame since the wedges 30 tend to hold the bolster in a centered position between opposing columns out of contact therewith. However, the opposing surfaces of the bolster and the columns (see webs 18 and 19 and bolster surfaces 38 and 39) are vertically rectilinear and closely spaced. Hence, the columns are important as guides for the bolster and frequently function as such as the wedges yield in one longitudinal direction or other with respect to the side frame. The wedges 30 are at close clearance with webs 18 and 19 and, hence, in guide relation therewith.

The side frame lateral walls 21 and 22 of each column are spaced to provide an opening extending from the bolster opening to the window 44 or 45 in each longitudinal direction from the bolster opening. Each of the windows is formed by a column and portions of the tension and compression members extending outwardly from the bolster opening to converge and join in a juncture portion of conventional type, such as a journal box or the pedestal jaw 47 shown. Integral with each side wall 42, and facing outboardly of the truck 3, is a pry bar receiving boss 48 terminating in an outer face 49 defining an opening 51 as hereinafter described.

As shown in FIGS. 1 and 3, the bolster 12 is disposed at a height within the opening 10 corresponding to a fully loaded condition of a vehicle. At this elevation, it is apparent that the longer web 53 of the wedge 30 defining its friction surface 31 is substantially coextensive with the recessed surface 32 of the bolster. This is desirable because of the greater amplitude of rubbing action within the snubbing system on a loaded vehicle. However, regardless of the height of the bolster within the opening 10, the wedges 30 and the chocks 36 maintain the same approximate position within the side frame between the bolster and a pair of supports 54, 55, as shown. These supports are integral with the frame on a horizontal alignment generally coinciding with the upper halves of the columns. Each support has a flat surface 54a or 55a generally parallel to a slightly rounded surface 57 of the adjacent wedge 30. The left side of FIG. 1 clearly shows the projecting and re-entrant relationship of the chock 36 and the support 54 as outlined in a vertical plane of cross section extending longitudinally of the side frame.

An important feature of this invention is that the support surfaces 54a and 55a are spaced with respect to adjacent wedges with a removable chock 36 interposed between each wedge and its respective opposed support surface.

The web 58 of each wedges which defines the chock-engaging surface 57 extends, in respect to a vertical plate, in angular converging relation with the friction surface 31 toward an approximate point 59 allowing for the fact

that the surface 57 is slightly rounded. The web 58 is relatively short as compared with web 53 because, if extended in an upward direction, excessive length would interfere with insertion of a pry bar through the boss opening 51 and its application to a cross-web 61 of the wedge; if the web extends downwardly beyond the lower limit shown, excessive length would then interfere with removal of the spring 35 and the wedge 30 during disassembly. As inferred above, the undersurface 61a of the web 61 functions as an upper seat for the spring whereas its upper surface 61b receives the end of a pry bar 63 inserted into the side frame, as shown in FIG. 5. This latter figure shows the pry bar fulcruming about a surface 64 forming the upper portion of the periphery of the opening 51. With the pry bar so positioned, upward swinging thereof exteriorly of the side frame forces the wedge downwardly in a direction parallel to surfaces 31 and 32 with resulting compression of the spring 35.

With attention, for example, to the right side of the frame, as shown in FIG. 1, the chock 36 drops out of the region between the support 55 and the wedge 30 when the wedge is depressed sufficiently to increase the distance between the wedge surface 57 and the support surface 55a by an increment greater than the length of the surface 66 of a lip 67 of the chock. The chock 36 is illustrated in FIG. 5 in the act of dropping out of the aforesaid region. The chock has another lip 68 which, together with lip 67 overlap the support 55 adjacent the upper and lower ends of the support surface 55a and prevent shifting of the chock relative to the support. The web 69 of the chock defines a flat surface 71 adapted for engaging the support surface 54a and 55a. The surface 71 is parallel to the surface 72 defined by another web 73. However, any construction of the chock may be adopted which provides the equivalent of lips 67, 68 and surfaces 71, 72.

As shown, a lower seat of the spring 35 is formed within the tension member 6 by a rib 74 extending along a vertical, longitudinal central plane of the side frame. The rib is stepped to provide an abutment of fixed position in the side frame, such as a surface 75, which extends underneath the spring. Each column has a transverse rib 76 in its lower portion with its general plane perpendicular to the axis M—M of the spring. The rib 76 has a semi-circular indentation at 77 complementary to the external periphery of the spring. In this manner the ribs 75, 76 cooperate to provide a pocket for receiving the lower end of the spring.

In removing one of the wedges 30, the chock, the spring, and the wedge are withdrawn from the side frame in the order named, first in the longitudinal direction of the frame within opening 23 to the nearest window 44 or 45, and then transversely out through the window.

As indicated before, the chock is first removed by prying downwardly on the wedge until sufficient clearance is obtained for the chock to drop out of overlapping relation with its respective support 54 or 55. Pressure on the wedge and the spring by the pry bar is then released. The spring at relaxed length allows adequate room in the opening 23 to lift the spring from the seat on the webs 75 and 76. After lifting the spring with the wedge seated on the upper end thereof from the lower seat, the lower end of the spring is swung toward the adjacent window and removed. Meanwhile, the wedge 30 has dropped into the lower portion of the opening 23 and may be extracted from the frame by reaching into the opening 23 from the adjacent side frame window. Installation of the wedge is carried out in an order reversed to that just described for disassembly. Such manipulation of the parts of the friction system may be carried out without otherwise disturbing any part of the car truck of a railway vehicle in any condition of loading.

FIGS. 8 and 9 illustrate another embodiment of the invention differing primarily from the earlier described embodiment of FIGS. 1 to 5 by a relatively inverted direction of the wedges 30 effecting a wedging relation with

the bolster 12 and the chock 36. In the side frame 80 of this latter embodiment, the chock supports 81 and 82 are on a horizontal level with the lower halves of the side frame columns 84, 85. The chock-engaging surfaces 81a and 82a face obliquely with the horizontal and upwardly toward the upper half of the bolster opening 86. Each column is separated as in the earlier described embodiment, to provide openings contiguous with the bolster opening 86 extending longitudinally of the frame between the side walls thereof into contiguity of the windows 88 and 89.

Each column 84, 85 has a pry bar boss 96 integral with and protruding from the outboard wall in the lower half thereof. In its structural details, the boss 96 is similar to the boss 48 of the earlier described embodiment.

To remove either chock 36 from the side frame 80, the wedge 30 cooperating therewith must be pried upwardly to obtain the clearance between the wedge and the opposing chock support 81, 82 which will allow movement of the chock away from its respective support sufficiently to displace lips 67 and 68 out of overlapping relation with the adjacent support 81 or 82. When this occurs, the chock is then lifted from the region between the chock support and the wedge. A hole 91 in the center web of each chock facilitates the manual handling thereof. With the chock removed, the pry bar may be manipulated to allow the wedge to settle downwardly to release the spring 35 from its upper seat 93 or 94. The spring is then removed through the adjacent window. Thereafter, the wedge 30 may be lifted out of the frame along the same path along which the chock and the spring were removed.

FIGS. 10 to 17 illustrate a further embodiment wherein a side frame 100 and a friction wedge 101 differ in some details from their counterparts 4 and 30, respectively of the first described embodiment illustrated by FIGS. 1 to 7. The frame 100 comprises a pair of chock-supports of which support 103 is analogous to chock-support 55 of the earlier embodiment.

The presently described embodiment illustrates the possibility of decreasing the distance between the chock-support and the bolster or bolster-opening when compared with FIGS. 1 to 7 by making a pry-bar receiving boss 105 of the frame and the wedge 101 correspondingly narrower in the horizontal longitudinal direction of the frame. Such dimensional reduction has advantages of reducing the obstruction of the frame window 106 by the chock-support, reducing the size of the wedge for more facile passage through the window, and facilitating passage of the spring 35 through the window and under the chock-support.

FIG. 17 is drawn in specific reference to the embodiment of FIGS. 10 to 16 but is illustrative of critical geometric relationships existing between the chock-support, the chock, the friction wedge, and the bolster, of all embodiments herein described. Line 104 represents a datum plane within the bolster opening of the side frame normally occupied by the bolster surface 32. In practice, the bolster moves relative to the wedge in this plane to effect bolster snubbing action. The corner 101b is the portion of the wedge furthest from plane 104 and the distance X between the line 104 and the corner 101b represents the maximum dimension of the wedge in the longitudinal direction of the side frame. As the wedge moves along the plane 104, e.g., when inserting the spring 35, the corner 101b traverses a path indicated by the dotted line M—M parallel to the surface 32.

A necessary feature of this invention is that the path M—M has a clearance E (FIG. 17) with the chock-support edge 103b as shown. A vertical projection of the edge 103b parallel to surface 104 follows along line P—P. Dimension Y represents the distance of the corner 103b from the surface 32 and, in this invention, must necessarily be greater than dimension X in order that the wedge may be elevated to levels within the frame placing its

corner 101b above the support corner 103b when maneuvering the spring into position underneath the wedge as illustrated in FIGS. 12 and 13.

In the embodiments herein described, the opposing surfaces of the chock-support and the wedge, e.g., surfaces 103a and 101a, are approximately parallel and, hence, the chock 36 takes a rectangular conformation. While such rectangularity is not critical, it illustrates the essential function of the chock, viz., to establish a spacing between the chock-support and the wedge which will position the wedge at a level along the bolster surface 32 or plane 104 and provide correct spring compression whereby a desired snubbing relationship and movement range between the wedge and the bolster is established. Primarily, the thickness of the chock as measured by dimension Z determines the operable level of the wedge.

The second essential function of the chock is that it may interlock with the chock-support and be removable from its position thereon only when the wedge is forcibly depressed to a level such as illustrated in FIG. 14, allowing disengagement of the chock from its support and passage thereof between the support and the wedge.

It is essential in this embodiment, as well as in the previously described embodiments, that the friction wedge be traversable through the window and into the space between the vertical webs of the tension member (see member 107 of the frame 100) and then transferable under the chock-support 103 into the region normally occupied by the chock, the spring and the wedge.

In the preliminary stages of assembly, the wedge 101 is passed through positions as shown in FIGS. 10 and 11, whereupon the spring may be inserted through the window and under the chock-support as shown in FIG. 11 and thence into the socket-like seat provided by the wedge 101 as shown in FIG. 12. The turning maneuver required to bring the spring into position under the wedge is facilitated by a concave undersurface 108 of the support 103. In bringing the lower end of the spring into position on the spring seat 109 as shown in FIG. 14, the lower end of the spring passes over a rib 110 as shown in FIG. 12 which guides the spring over the top of the center boss 111 of the spring seat. The rib has the further function defining the spring seat and holding the spring in place.

A pry bar 112 may be inserted through the opening 113 of the boss 105 and used as a lever to depress the wedge, e.g., $1\frac{1}{2}$ inches below its normal working position, and compress the spring 35 as shown in FIG. 14. The inner vertical sides of the boss 105 defining the opening 113 are substantially parallel throughout the length of the boss. The boss tapers with respect to its longitudinal vertical center plane away from the side wall of the frames to permit the pry bar to fulcrum at the outer extremity of the boss. The thickness of the pry bar 112 in a horizontal direction is nearly equal to the spacing of the inner sides of the boss. Hence, when the pry bar is inserted through the boss, a guide relationship exists between the inner sides of the boss and the pry bar which restricts the movement of the pry bar within a vertical plane when used to depress the wedge out of its operative position. The reason for this guide relationship is explained below.

As FIG. 14 further illustrates, the chock 36 may be inserted (or removed from) between the surfaces 103a and 101a. With the chock placed against the surface 103a and interlocked with the support 103 by its flanges 67 and 68 as shown in FIG. 15, pressure of the pry bar on the wedge 101 may be relaxed to permit the spring 35 to expand. Thereupon, the parts assume the operative positions shown in FIG. 15 with the chock 36 locked in place.

The wedge 101, which may be reduced in dimension in the direction of dimension X as compared to the wedge 30 hereinbefore described, is further distinguishable by two ribs 115 and 116 which extend along and are merged with the upper side of the transverse web 117. The web 117 also merges with the upper end of the chock-engaging

web 120 to form a corner 101c at the upper extremity of the surface 101a. The ribs 115 and 116 are shown terminating in spaced relationship with both the corner 101c and the friction web 119. The end surfaces 115a and 116a of these ribs slope downwardly away from the bolster engaging web 119 at an acute angle therewith. As the surfaces 115a and 116a are in a transverse alignment with the opening 113 in a direction parallel to the plane of the engaged bolster and wedge surfaces, they are engaged in a manner apparent from FIGS. 14 and 15, such as required during insertion or removal of the chock 36. The angularity of the surfaces 115a and 116a with the vertical plane of movement to which the pry bar is restricted within the opening 113 causes the pry bar to urge the wedge toward the bolster as the pry bar pushes the wedge lengthwise of the bolster surface. The resulting equilibrium of the pry bar force with the forces exerted on the wedge by the spring and the friction with the bolster 12 maintains the wedge in face-to-face contact with the bolster when the wedge is forced downwardly for chock removal or insertion.

Thus, the angle of the rib surfaces 115a and 116a causes the pry bar to engage the wedge in a manner that avoids the tilting that is likely to be incurred with pressure upon the wedge at a point substantially closer to the web 120, or when the area of the bar-receiving area of the wedge does not slope downwardly away from the bolster. Also to be noted is that the pry bar engages the ribs 115 and 116 at an adequate distance from the support 103 to allow the chock to tilt toward the pry bar and away from the support 103, as shown in FIG. 14. The chock thereby avoids the interference of the pry bar that would be incurred by the engagement of the pry bar with the wedge area closer to the corner 101c.

In assembling trucks built in accordance with either of the three main embodiments herein described, a bolster is readily inserted into the opening of either side frame of the truck by endwise movement of the bolster into the opening at any level. If the bolster springs 14 are not in place, the usual procedure is to insert the bolster into the bolster-opening of the side frame and raise it to a level at which the springs 14 may be placed on their seat defined by an upper surface of the tension member. The bolster is then lowered to bring the spring seat thereof into contact with the upper ends of the springs. The absence of bolster lugs or other media of the bolster or side frame overlapping the other in the longitudinal direction greatly adds to the convenience and reduces the labor of assembling a truck. This advantage is brought about primarily by insertion of the interlocking means, namely the wedge, at a final stage of the truck assembly.

The terms and expressions which have been employed are used as terms of description and not of limitation, and there is no intention of excluding such equivalents of the invention described or the portions thereof as fall within the scope of the claims.

What is claimed is:

1. In a railway car truck:
  - (A) a side frame having
    - (1) transversely spaced walls,
    - (2) a transverse bolster opening,
    - (3) a support fixed between said walls to face toward said opening,
    - (4) a window in said walls spaced in the lengthwise direction of the frame from the bolster opening; and
    - (5) a second opening extending between said walls from the bolster opening to the window and past one vertical extremity of the support;
  - (B) a bolster extending through said bolster opening;
  - (C) a friction wedge having two sides diverging from its smaller end to its wider end, one of said sides normally engaging the bolster;
  - (D) a chock having a face engaging one of said wedge

- sides, the wedge and the chock being disposed between the support and the nearer side of the bolster with the other of said wedge sides against said bolster side and the chock against said support; 5
 (E) an abutment disposed between said walls in spaced relation with the support, and facing toward said wedge;
 (F) resilient means disposed between the wedge and the abutment while in a position fixed relative to the side frame and reacting with both to force the wedge into wedging relation with the bolster and the chock, and the chock against said support; 10
 (G) the chock and the support having cooperating detent portions overlapping in the longitudinal direction of the side frame and disposing the chock and the support in projecting and re-entrant relationship in a vertical plane extending in said longitudinal direction to maintain the chock in position on the support; 15
 (H) said wedge being movable out of engagement with the chock toward said abutment while in said fixed position through compressing said resilient means to increase the distance between the wedge and the support to an extent enabling such movement of the chock as to move said detent portions out of overlapping relationship and passage of the chock from the support through the second opening while the resilient means is compressed; and 20
 (I) said support being spaced across the second opening from other transversely extending portions of the side frame to enable passage of the wedge, the chock, and the resilient means to said window. 30
 2. The car truck of claim 1 wherein:
 (A) the spacing of the support relative to the bolster in a longitudinal direction of the side frame is greater than the maximum dimension of the wedge taken at its operative position in a direction parallel to said longitudinal direction whereby the wedge is traversable vertically along said bolster past the support. 35
 3. The car truck of claim 1 wherein:
 (A) the spacing of the support relative to the bolster in a longitudinal direction of the side frame is greater than the maximum dimension of the wedge taken at its operative position in a direction parallel to said longitudinal direction; and 40
 (B) said chock has a thickness in a direction transverse to opposing surfaces of the support and the wedge engaged by the chock disposing the wedge intermediately of upper and lower extremities of the bolster surface in frictional engagement therewith at operative positions of the bolster. 45
 4. The car truck of claim 1 wherein:
 (A) the spacing of the support relative to the bolster in a longitudinal direction of the side frame is greater than the maximum dimension of the wedge taken at its operative position in a direction parallel to said longitudinal direction; 50
 (B) said wedge has re-entrant means defining an abutment surface for receiving a pry bar disposed between said divergent wedge sides and said abutment surface faces generally in the direction in which the divergent sides converge; and 60
 (C) said wedge has a pry bar-receiving surface disposed along said smaller end between said sides and sloping at an acute angle relative to said one side toward the other side; and 65
 (D) said frame has an aperture defining a pry bar fulcrum in horizontally transverse offset relation with an open region vertically adjacent said abutment surface. 70
 5. The car truck of claim 1 wherein:
 (A) the spacing of the support relative to the bolster in a longitudinal direction of the side frame is greater than the maximum dimension of the wedge taken at its operative position in a direction parallel to said longitudinal direction; 75

- (B) said wedge has a pry bar-receiving surface disposed along said smaller end between said sides and sloping at an acute angle relative to said one side toward the other side, and said frame has a hollow boss projecting outwardly from one of said walls in horizontally transverse offset relation with an open region vertically adjacent said abutment surface; and
 (C) said boss has opposed vertical walls which are parallel in the transverse direction of the frame to define the pry bar guiding surfaces and an opening through the boss of approximately uniform width. 6. The car truck of claim 5 in combination with a pry bar adapted to pass through said opening;
 (A) said pry bar having a thickness nearly as great as the width of the opening for restricting the pry bar to angling movements within said opening approximately to a vertical plane.
 7. In a railway car truck:
 (A) a truss type side frame having
   (1) transversely spaced walls,
   (2) two columns spaced in the longitudinal direction of the frame to define a bolster receiving opening,
   (3) the windows spaced from the opening in the longitudinal direction of the frame;
 (B) one of said columns having a second opening contiguous with the first opening and extending therefrom in the said longitudinal direction to said windows;
 (C) a bolster extending in a direction transverse to said direction through the bolster opening in vertical guide relation with the columns;
 (D) a friction wedge having two sides diverging from its smaller end to its wider end and positioned in the second opening with one of said sides in slidably engagement with the side wall of the bolster;
 (E) a support fixed in said frame and spaced from the wedge in said longitudinal direction;
 (F) a removable chock having opposite faces engaging the support and the wedge;
 (G) a spring seat fixed between said walls in spaced relation with the support and facing obliquely toward said bolster-receiving opening;
 (H) a spring disposed between the wedge and the spring seat and reacting with both to urge the wedge into wedging relation with the chock and the bolster; the support and the chock having cooperating portions overlapping in the longitudinal direction of the side frame, and disposing the chock and the support in projecting and re-entrant relationship in a vertical plane extending in said longitudinal direction to maintain the chock in position on the support; said wedge being movable out of engagement with the chock toward said spring seat through compression of said spring to increase the distance between the wedge and the support to an extent permitting such movement of the chock as to move said detent portions out of overlapping relationship and passage of the chock from between the support and the wedge in a direction past said wider end while the spring is compressed; said support being spaced across the second opening from other transversely extending portions of the side frame for passage of the chock, the spring, and the wedge therethrough to said window.
 8. The car truck of claim 7 wherein:
 (A) the support is spaced longitudinally of the frame from parts of the column defining the bolster opening by a distance permitting free passage of the wedge in a vertical direction between the bolster and the entire support when the chock is removed from between the wedge and the support.
 9. The railway car truck of claim 7 wherein:
 (A) the wedge has a pry bar-receiving surface dis-

11

- posed between said sides at said smaller end facing away therefrom; and
- (B) said frame comprises a boss projecting outwardly from one of said walls in a transverse direction from a region vertically adjacent said smaller end to define a fulcrum surface offset outwardly from said wall, and said wall provides an access opening to said bar-receiving surface. 5
10. The car truck of claim 7 wherein:
- (A) the surface of the support engaged by the chock is generally parallel to the chock-engaging surface of the wedge; and said opposite faces of the chock have generally parallel oppositely-facing surfaces engaging the support and the wedge. 10
15. The car truck of claim 7 wherein:
- (A) said convergent wedge sides converge toward a point of intersection, and the wedge has a pry bar-receiving surface disposed between said sides facing toward said point;
- (B) said column comprises a wall facing outwardly of the truck in said transverse direction; and
- (C) said wall has a pry bar-receiving aperture opening into a region between said point and said bar-receiving surface. 20
25. The railway car truck of claim 9 wherein:
- (A) said wedge comprises an abutment disposed between said two divergent sides and the abutment has said bar-receiving surface on one side and a seat for said spring on its opposite side.
30. The car truck of claim 11 wherein:
- (A) said column wall comprises a hollow boss terminating outwardly in said transverse direction from the general longitudinal plane of the wall in an end portion defining said aperture.
35. The car truck of claim 11 wherein:
- (A) said wedge comprises a web defining said chock-engaging surface, and terminating, at the end thereof nearer said point, adjacent an edge of the pry bar-receiving surface.
40. The car truck of claim 10 wherein:
- (A) said overlapping detent portions of the chock comprise flanges extending past the upper and lower extremities of said support surface.
45. The car truck of claim 15 wherein:
- (A) a truss-type side frame having
- (1) transversely spaced side walls,
  - (2) two columns spaced in the longitudinal direction of the frame to define a bolster-receiving opening, and
  - (3) windows in the side walls separated from said opening by the columns; 50
- (B) a bolster extending transversely to said direction through the bolster opening with each opposite side surface in guide relation with the adjacent column;
- (C) each of the bolster side surfaces defining a vertically rectilinear recess and disposed within the transverse limits of the column, and portions of each column being spaced in said transverse direction to define an opening contiguous with the recess of the adjacent bolster and extending away therefrom to 60 a window;
- (D) a pair of friction wedges, each having divergent sides terminating at the wider end of the wedge and disposed partly in one of said recesses, and partly in the adjacent one of said contiguous openings; 65
- (E) a pair of supports fixed in the frame and spaced in said longitudinal direction at opposite sides of the bolster opening in spaced opposed relation with the respective nearer wedge;
- (F) a pair of chocks, each positioned between a support and a wedge in opposed relation therewith; each chock and support therefor having cooperating detent portions overlapping in said longitudinal direction and disposing the chock and the support in 75

12

- projecting and re-entrant relationship in a vertical plane extending in said longitudinal direction to maintain the chock in position on the support;
- (G) a pair of spring seats fixed between said walls at opposite sides of the bolster-receiving opening; each seat facing obliquely toward said opening and toward the closer one of said wedges;
- (H) a spring in opposed relation between each wedge and the spring seat facing theretoward and reacting with both to force the wedge into wedging relation with the bolster and the chock, and the chock against said support;
- (I) each wedge being movable out of engagement with the chock toward the spring seat facing theretoward against compression of the spring to increase the distance between said wedge and the adjacent support to an extent permitting such movement of the adjacent chock as to move the detent portions of the chock and the support out of overlapping relationship in passage of the associated chock from between the support and the wedge and into and through the second opening while the associated spring is compressed;
- (J) each support being spaced across the adjacent one of said contiguous openings from other transversely extending portions of the side frame to enable passage of the wedge, the chock, and the spring through said contiguous opening to the associated window.
17. The combination of:
- (A) a side frame;
- (B) a friction wedge;
- (C) a chock received by the frame for engaging one of two divergent sides of the wedge;
- (D) the side frame having:
- (1) two vertical columns spaced relative to each other in the longitudinal direction of the side frame to define a first opening for receiving said bolster; at least one of said columns comprising:
    - (a) a pair of webs defining one side of said opening and spaced in said transverse direction on opposite sides of a vertical longitudinal plane of the frame to define a second opening communicating with the first opening, said one column having
    - (b) upper half and lower half portions;
  - (2) a support fixed within said frame in generally horizontal relation with one of said half portions to face at an inclination with the horizontal through the second opening into a portion of the first opening on a level with the other half-portion of said column,
  - (3) a spring seat spaced from the first opening in a longitudinal direction of the frame through the second opening in generally horizontal fixed relation with the extremity of said one column defined by its other half portion, said seat facing along said vertical plane toward said one half portion;
  - (E) said frame having a window spaced by said one column from the bolster opening and communicating with the second opening;
  - (F) said chock having two oppositely-facing surfaces of which one is adapted to engage the face of the support and the other is adapted to engage said side of a wedge;
  - (G) said chock comprising a portion overlapping a portion of the support in said longitudinal direction and disposing the chock and the support in projecting and re-entrant relation in said longitudinal plane for preventing movement of the chock in the plane of said face;
  - (H) said support being spaced in its entirety from surfaces of said column partly defining the first

opening to enable vertical passage of the wedge in its entirety between said support and a bolster in operative position within said first opening;

(I) said support being spaced across the second opening from other transversely extending portions of the side frame, and said second opening being open, to enable passage of the chock, the wedge, and the wedge spring normally used in said frame from operative positions to said window. 5

18. The combination of claim 17 comprising:

- (A) a friction spring having a free length which, when seated on said seat, extends upwardly from the seat through a region between said support and a bolster disposed in said first opening;
- (B) said seat being disposed in a lower part of the frame; 15
- (C) said second opening extending from said first opening to a window in the frame;
- (D) and said support having a notch extended up-

wardly from its lower edge to an extent permitting passage of said spring therewith from said window to said position.
